WEB SUPPLY MECHANISM FOR PRINTING MACHINES

John R. Tomlin, Brooklyn, N. Y., assignor to R. Hoe & Co., Inc., New York, N. Y., a corporation of New York; Irving Trust Company, trustee

Application January 29, 1932, Serial No. 589,566

29 Claims. (Cl. 242—75)

This invention relates in general to web supply mechanism for use with machines which print or otherwise operate upon webs of paper or similar material that are drawn from rolls and especially high speed rotary printing machines. More particularly the invention relates to a novel mechanism for controlling the tension of a web running to a printing machine so that tension will be applied to a web of the smaller or exhausting roll of a pair of web rolls mounted on a support and then automatically transferred to a web of the other or spare roll as the latter replaces the former. The device makes use of tension or braking mechanism of the character shown and described in co-pending application of John R. Tomlin, Serial No. 505,551, filed Dec. 30, 1930, now Patent No. 1,930,733, granted Oct. 17, 1933, and has for its object the provision of means whereby tension or regulating action is communicated automatically from one web to another of a plurality of web rolls revolvably mounted on a common web roll support connected to a printing machine, without interruption to the operation of the said machine.

A further object is the provision of a web roll carrier adapted to rotatably support each of a plurality of web rolls in operative position for supplying a continuous running web to a printing machine, and to apply and transfer a tensioning action from the web of one web roll to another, so that the feeding of the running web to the printing machine may be effected under operating conditions of the highest efficiency and without interruption or retardation of the operation of the printing machine.

Another object is to provide means for revolvably mounting a pair of web rolls on a support and connecting said web rolls to a common braking mechanism by clutch means in such wise that resistance will be opposed to the rotation of the roll in immediate use until the said roll has been replaced by another and then applied to the latter automatically, without stoppage or retardation of the said machine.

A still further object is to provide a web roll support particularly designed and adapted to operatively mount two web rolls in proximity to each other in such wise as to effect the utmost economy of space.

It is also an object to provide a web roll support of generally improved construction, whereby the device will be simple, durable and inexpensive in construction, as well as convenient, practical, serviceable and efficient in its use.

With the foregoing and other objects in view, which will appear as the description proceeds, the

invention resides in the combination and arrangement of parts, and in the details of construction hereinafter described and claimed.

The preferred embodiment of the invention is illustrated in the accompanying drawings, 5 wherein:

Figure 1 is a front view, with parts broken away, of a web roll carrier to which the invention has been operatively applied;

Figure 2 is a top plan view, partly in section, 10 looking in the direction of the arrow 2 of Figure 1;

Figure 3 is a front view of a modified form of the invention;

Figure 4 is a top plan view of the modified form 15 of the invention looking in the direction of the arrow 4 of Figure 3;

Figure 5 is an enlarged elevational detail view, 20 partly in section, of details forming a part of an associated tension device for applying and transferring braking action from one web roll to another;

Figure 6 is a transverse sectional view taken on line 6—6 of Figure 5 looking in the direction of the arrow; and

Figure 7 is a transverse sectional view, partly in 25 elevation, taken on line 7—7 of Figure 2, looking in the direction of the arrow.

In the drawings, A and B designate web rolls which may be for example an exhausting and a replacement or spare web roll respectively, rotatably mounted upon an adjustable web roll carrier 30 D embodying one form of the invention.

The web roll carrier D comprises a supporting frame or structure which includes uprights or pedestals 11 and 12 respectively. The upright 11 is fixedly secured to a floor or foundation while the upright 12 is slidably mounted in any suitable manner upon a base plate 13 for providing axial or longitudinal movement to a portion of the web roll carrier assembly which coats with the fixed 40 portion thereof in adjustably supporting the plurality of web rolls A and B.

The web rolls A and B are supported on yoke members or arms 14, 15 each of which is formed with a pair of hubs or bearing heads 16, 17 having spaced apertures formed therein for the sliding reception of twin shafts 18 and 19, the hubs being adjustably secured to the twin shafts 18, 19 in any suitable manner as by set screws 20. The shafts 18, 19 are joined by a brace or web 21 having twin collars or heads 22 in which the said shafts 18, 19 may be slidably secured or locked thereto as by the set screws 23. The ends of the yoke member 14 have protruding roll supporting spindles 24 with tapering portions or sleeves 25 to 55

tatably supported thereon, a pair of which latter are adapted to be thrust into and out of the cores of the web rolls at one end by manipulating the hand wheels 26 when the web rolls are mounted 5 on and taken off of the said yoke members. The mechanism for adjusting the spindles 24 into and out of the cores of the web rolls may be of a type similar to that shown in patent of Lamatsch, No. 1,859,301, dated May 24, 1932, for Web roll support, and need not be described in detail here.

The other yoke member 15 shown in Figures 1 and 2 is provided with means forming an important feature of the present invention as will hereinafter appear, which coacts with an adjustable 15 braking or tension device or assembly E for automatically and alternately transferring a braking or regulating tension from the web of one revolving web roll A which may be an exhausting roll to the web of another rotating web roll B which 20 may be a replacement or reserve web roll. This tension on the web is effected by the resistance offered to the rotation of the web rolls by the braking or tension device E. Each of the opposite ends of the yoke member 15 on either side of the twin hubs 17 comprises, as best shown in 25 Figures 5 and 6, a hollow annular member or casting 27 which may be of the conventional form shown and which serve to house the free or overrunning clutch and roll core-engaging assembly 30 28 forming a component part of present invention and of the means which directly coact to support the web rolls A and B by engagement with the cores 29 thereof.

The clutch and core engaging assembly 28, 35 which is rotatably mounted in the housing 27, comprises a sleeve 31 to which is fastened by screws 32 a plate 33 having a hole 34 in the marginal edge of which is an annular pocket 35 adapted to receive a fibre washer 36 or other suitable 40 material for preventing the seepage of oil from the interior of the sleeve 31 wherein a spindle 37 having an outer tapered core-engaging end 38 is revolvably mounted by means hereinafter described. The inner annular surface of the sleeve 31 is provided with an annular inwardly directed 45 flange 39, on either side of which are arranged the roller and ball bearings 41, 42 respectively secured in the races or guides 43, 44 which are seated in somewhat relative staggered relation 50 on the said inner surface of the sleeve 31. By inspection of Figure 5, it will be seen the spindle 37 is formed with an enlarged portion or external flange 45, which is adjacent to the outer surface 55 of the plate 33, and is also provided with a series of integrally-formed, annular bearing-supporting or reduced portions 46, 47, 48, and a reduced end 49,—all of which are arranged in concentric and stepped relation, the portion 46 coacting with the washer 36 to retain oil within the sleeve 31, while 60 the portion 47 and the reduced end 49 serve as bearing surfaces for the roller and ball bearings 41 and 42 which permit the free rotation of the said spindle. On the portion 48 a sleeve or annular member 51 is secured by keys 50, and this 65 member has recesses or pockets 52 accommodating rollers 53 confined between guide strips 54 arranged in pairs and suitably secured to the annular member. Each of the rollers 53, as best shown in Fig. 6, is engaged by a plunger assembly 40, 70 comprising a small block or plate 55 having an arcuate surface and provided with a stem 56 received in a spring 57 positioned in a recess 60 communicating with each of the pockets 52, the spring 57 pressing against the plate 55 to normally 75 and yieldingly maintain the roller 53 against the

inner surface or inwardly directed flange 39 of the sleeve 31, but permitting the said rollers to have movement against the resistance of the said spring for a purpose appearing hereinafter. To the outer extremity of the reduced end 49 of the 5 spindle 37 a plate 59 is fastened in any suitable manner as by the screw 61. The plate 59, it will be noted, serves to retain the ball bearing 42 against the side of the flange 39 in order to maintain the bearing 42 in correct alignment for seating on the reduced end 49, of spindle 37 and for coacting with plate 33 and roller bearing 41, to maintain the sleeve 51 and its rollers 53 on the flange 39.

A second plate 62 which is recessed as at 63 15 to receive the smaller plate 59 has a boss 64 which is shouldered or reduced as at 65 to provide a reduced end 66 on which a collar 67 having a sprocket or gear 68 is splined or keyed. The plate 62 is secured by the screws 32 and screws 20 69 to the sleeve 31 and aids in retaining the bearings and spindle 37 hereinbefore mentioned in correct alignment in the sleeve 31. As best shown in Figure 5, the means for rotatably supporting the core-engaging assembly 28 within the housing 25 27 includes a thrust ring 70 secured by a series of screws 70' to the sleeve 31. Roller bearings 27' arranged on either side of the said thrust ring 70 and positioned between the housing 27 and sleeve 31 serve to rotatably support the latter when 30 torque is being transmitted from the spindle 37 to the said sleeve 31 and thereby to the plate 62 and sprocket 68 which is operatively connected, as hereinafter described, to the tension device E.

To rotate the web roll support when required 35 in order to alternately bring one roll or another to a position suitable for feeding a web to a printing machine or joining the web of the replacement roll to the exhausting roll, the twin shafts 18 and 19 on which the yoke members 40 14 and 15 are secured, are shouldered as at 71 to provide reduced ends 72, 73, which are received in holes 74 formed in spindle blocks or trunnion members 75, 76, the latter being fastened against the shoulders 71 of the twin shaft 18, 19 by nuts 45 77 threaded on extremities 78 of the shafts 18, 19 and engaged against washers 79 abutting shoulders 81 on the blocks 75, 76. The spindle blocks 75, 76 have projecting hubs or journals 82, 83 respectively on the latter of which a worm 50 gear 84 is secured as by the key 85. The hubs or journals 82, 83, which serve as pivots or axles for the entire assembly between the blocks 72, 73, are mounted on journal bearings 86, 87 secured to the uprights 11 and 12 respectively. As 55 clearly shown in Figure 2, the spindle block 76 is provided with a hole or passageway 88 through which a shaft 89 having a reduced end 90 is passed, the latter being connected at one end by a coupling 91 to the coacting tension device E 60 mentioned above, the details of which latter in themselves form no part of the present invention. The reduced end 90 of the shaft 89 is received in a pocket 92 formed in the brace 21 and is slidably keyed or splined to an element 65 94 having two sprockets 95, 96 secured to or formed integrally thereon. The element 94 which, as shown in Figure 2, is positioned in a pocket 97 formed in the hub 98 of the yoke member 15, is shouldered as at 99 and has a reduced 70 end 101 which is rotatably received in a hole 102 provided in the inwardly directed hub 103 of a plate 104 which is secured in a suitable manner as by the screw bolts 105 to an annular flange 106 formed on the hub 98 of the yoke member 75

15 adjacent the outer portion of the pocket 97. The end of the inwardly directed hub 103 of the plate 104, it will be noted, is seated against the shoulder 99 of the element 94 thus confining the 5 latter in the pocket 97 in the position shown until the plate 104 is removed.

Referring to Figure 1, it will be seen that the worm gear 84 is engaged with a worm 107 secured on a shaft 108 to which a gear 109 is fastened, the latter being operatively connected to a motor (not shown) so that when the latter is actuated the worm gear 84 fastened to the spindle block 16 will rotate causing the roll carrier D or rather the yoke members 14, 15 thereof to turn for 10 swinging the web rolls A and B in the desired 15 positions.

By further inspection of Figure 1, it will be noted that the tension device E which is supported on the bracket 111 fastened on or formed 20 integrally with the upright 12 together with an assembly including an electric motor 112 connected by gears 113, 114 to a worm gear 115 fastened on a shaft 116 threadedly engaged in a block 117 rigidly secured to the base plate 13, is 25 slidably mounted on the said base plate 13, so that when the motor 112 is actuated the entire assembly shown at the right-hand side of Figure 30 1 including shaft 89 will move or reciprocate in the direction of the axis of the said shaft 89 for the purpose of obtaining the proper adjustment of the roll of paper to provide the correct or 35 desired margins on the newspaper or magazine being printed. The tension device E which is described and illustrated in the pending application Serial No. 505,551, filed Dec. 30th, 1930, as alluded to above, serves to provide regulating means for a web roll controlling mechanism that will act to vary the braking action as the web roll decreases in size.

Assuming for example that A and B are 40 exhausting or expiring and replacement web rolls respectively and that it is desired to substitute the web of roll A by the web of roll B without interruption to provide what is called a "flying 45 paster" or web join, and further assuming that the web of roll A is traveling to a printing machine, the rotation of the said roll A will cause the rotation of the spindles and sleeves 24 and 37 at the left and right-hand sides of the web roll 50 A in the direction of the arrows as shown in Figures 1, 5, and 6 and consequently revolve the spindle 37 and the annular member 51 keyed thereto, thereby binding or jamming the rollers 53 between the inner surface of the sleeve 31 55 and the surface of the pocket 52. This coaction of the spindle 37 of the running roll with the sleeve 31 will cause the revolution of the latter and consequently the rotation of the sprocket 68 on the collar 67 forming a part of the plate 62 fastened to the sleeve 31. The sprocket 68 is connected by a chain 118 or other suitable means to the sprocket 95 of the sprocket element 94, the other sprocket 96 of which is connected by a second chain 119 to the sprocket 68 on the collar 67 fastened to the spindle 38 of the 60 replacement web roll B. The spindle assembly supporting the web roll B is practically identical with the spindle assembly supporting A, but in the case of the web roll B it is to be noted that the sprocket 68 thereof, while the web of the 65 exhausting roll A, is traveling to the printing machine, is now turning the sleeve 31 which will over-run the spindle which occurs as the rollers 53 in the pocket 52 press against and push back the small plunger assemblies 40 when the sleeve 70

75 31 rotates with the driving sprocket 68. No movement therefore, will be communicated to the web roll B and consequently the tension device E will function solely to regulate the tension of the web of the roll A. When, however, the replacement web roll B has been bodily swung by the web roll carrier D which includes the worm and gears connected to the motor (not shown) on the shaft 108, to the desired position preparatory to making a flying paster, and its periphery 10 has been engaged in the usual manner by power driven means (not shown) to equalize its peripheral speed with that of the exhausting web roll A, it will be observed that when the web of the latter has been joined to the web of the replacement roll B and separated from the stub of the exhausting roll A, the sleeve 31 will be operatively connected or bound to the spindle 37, in the manner described above. A resistance to the rotation of the replacement web roll B will now 15 take place in the manner described above in connection with web roll A. Under all circumstances the tension device E through the intermediary of the shaft 89, the clutch and core-engaging assemblies 28 and associated parts will function to 20 automatically regulate or brake the web roll being used, no tension being communicated to the web of the replacement web roll B during the transfer process until the substitution of one web for another has actually been made and the stub 25 of the exhausting roll A has been separated from the portion of the web of roll A now spliced to the web of roll B. Also it is to be noted that the device will function automatically to apply tension to the web of the smaller of a pair of web 30 rolls mounted on a support during the process of the substitution above-described, and until such substitution has actually been made since the angular speed of the core of the smaller roll will increase as the said smaller roll decreases 35 in diameter and will invariably be greater than the angular speed of the core of the replacement web roll up to and including the time when the web of the expiring web roll has been severed from its stub. 40

45 As shown in Figures 1 and 2, the yoke members 14 and 15 may be slid or adjusted on the twin shafts 18, and 19 by loosening the screws 20 on the hubs 16, 17 in order to accommodate web rolls of various widths as indicated on dotted lines. 50

55 In addition to the automatic regulation and transfer of the braking action applied to the core of the expiring web roll to that of the replacement web roll, it is to be noted that by the use of twin shafts 18, and placing same in spaced relation between and adjacent the web rolls A and B it is possible to arrange the web rolls so that their peripheries are quite close, or separated just sufficient to allow the tension transmitting shaft 89 to be introduced therebetween, thus effecting 60 an economy of space which is another feature of the present invention and one of the most essential desideratum in the web roll handling and printing departments of modern newspaper and magazine plants. The economy of space 65 effected by the present web supply mechanism is best illustrated in Fig. 7 where it will be observed that by placing the twin supporting shafts between the exhausting and replacement rolls and removed from the vertical line joining their respective axes, it is possible to bring the said rolls into a superposed position with their adjacent peripheries separated by a narrow space just sufficient to allow clearance for the tension transmitting shaft 89. It will be observed that the 70 75

5 twin shafts or axial supports 18, 19 are arranged between the pair of web rolls and positioned within parallel planes common to the peripheries of the web rolls. Stabilization and stiffening of the immediate supporting structure of the web rolls by the use of the twin shafts and associated parts are also desirable concomitants of the present design and construction.

10 In Figures 3 and 4 I have illustrated a modified form of the invention which makes use of two pairs of the over-running clutch and core-engaging assemblies, secured in casings 27, practically similar to those described above. The present embodiment of the invention employs a counter-shaft 124 hereinafter mentioned and arranged at one side and in the same plane with a shaft 125 which has yoke members 126, 127 slidably and adjustably secured thereon by set screws 128 threadedly engaged in the hub 129 of the said 15 yoke members 126, 127. Such parts of the modified form of the invention as are practically the same as those described in detail above will only be referred to in the present form by indicating their actual connection to other details of the 20 mechanism for coaction with same.

25 By inspection of Figure 3 it will be seen the shaft 125 on which the hub 129 of yoke members 126, 127 are secured, is rotatably mounted in journal bearings or heads 130, 131 formed on or 30 secured to supporting pedestals 132, 133. On the journal bearing 130 a tension member E of the type described above is fastened, an operative driving connection between the device E and the shaft 124 being obtained by a chain 134 and a pair 35 of coating sprockets 135, 136 connected to same, as clearly indicated in Figure 3. Fast with the sprocket 136 is a gear 137 rotatably mounted on the shaft 125 and meshing with a gear 138 fastened on the countershaft 124, the latter being 40 held in spaced relation to the former by bearing hangers 139, 140 which are preferably spliced as by the key or spline 141 to the shaft 125 and thus will rock or swing about the latter as an axis when the said shaft 125 is turned by the 45 worm gear 84 which engages the worm 107 on the shaft 108 having a connection to a driving motor (not shown) of the same general type as the mechanism shown in Figure 1 and described above. To the right-hand end of the shaft 125 50 is a hub 142, which may be a part of the worm wheel 84, is fastened. When the pedestal 133 and connected assembly including the motor 112 are slid on the base plate 113 as described above in connection with the details shown at the 55 lower right-hand side of Figure 1, the hub of the bearing hanger 140 and the hub 142 between which the hub 131 of the pedestal 133 is confined, will serve to convey the shaft 125 in an axial direction, thus permitting the withdrawal of the 60 particular spindle from the core of one of the web rolls after one or both of the set screws 128 have been turned to permit the adjacent hub or hubs 129 of the yoke member 126 or 127 to be slid on the shaft 125 thereby allowing the exhausted web roll H to be taken off and replaced.

65 As best shown in Figure 4 the hubs 129 of both yoke members 126, 127 of the modified form of the invention are secured to bearing collars 143, 144 by screw bolts 145, the collars 143, 144 supporting the counter-shaft 124 in spaced relation to the shaft 125. Secured or keyed to shaft 124 70 are members or collars 146, 147 each having a pair of sprockets 148, 149, 150, and 151. The sprockets 148 and 151 are adapted to be connected by chains 152 (see Figure 3) to sprockets

153, 154 respectively fastened in the spindles 27 of the lower web core engaging members, while the sprockets 149 and 150 are connected by chains 152' to sprockets 155 and 156 on the upper spindles 27 of the web core engaging members, 5 from which it will be seen that when a web roll which may for example be an exhausting roll, is revolving by power driven means, rotation will be communicated to the clutch and core engaging assembly 28 arranged on the said rotating 10 web roll and thence via sprockets 148, 149, 150 and 151; and sprockets 153, 154, 155, and 156 inclusive and chains 152 and 152', to the countershaft 124 which is connected by gears 137, 138 to tension device E whose automatic regulating 15 or braking action has been alluded to above.

20 The countershaft 124 is mounted in journal bearings 157, 158 secured to or formed integrally with hangers 139, 140 and is secured against axial or longitudinal displacement during operation by 25 a collar 159 fastened to one end thereof and engaged against the journal bearing 158, and by the washer 161 which is pressed by the gear 138 against the journal bearing 157, the gear 138 being held to the shaft 124 by a screw 162 30 threaded in the reduced end of the said shaft 124.

35 The operation of the modified form of the invention shown in Figures 3 and 4 in large measure parallels the operation of that shown in Figures 1 and 2 since the same type of over-running clutch and core engaging assemblies are used. In the present instance, however, instead of the twin shafts 18 and 19 of Figures 1 and 2, the yoke members 126, 127 are adjustably secured on the shaft 125 which is rotated on its axis and shifted 35 laterally when desired by the assembly illustrated at the lower right-hand side of Figure 3, which is similar to that shown in Figure 1.

40 In the present instance, assuming the lower or exhausting web roll H to be revolving, tension or regulating braking action will be communicated thereto by the tension device E through the intermediary of the countershaft 124, the sprockets 148, 153, 154, 151 and chains 152, while the over-running clutches in the casings 27 of the 45 upper portions of the yoke member 126, 127 will idle until the upper web roll J is rotated at a speed sufficient to revolve the sleeves 31 supporting same at an angular speed greater than that of the spindles 31, as set forth above. By the 50 arrangement of the two pair of over-running clutch and core engaging assemblies 28 and the countershaft 124, tension or braking action from the tension device E may be distributed equally and automatically to the spindles of the web rolls 55 H and J, thereby achieving a very uniform or stabilizing action on the one or both web rolls H and J which has been found to substantially lessen vibration in addition to which the danger or possibility of tearing or rupturing the 60 core of the web roll when starting up is greatly minimized as the force necessary for overcoming the inertia of the web roll is now distributed at two points or both ends of the said web roll. The tension device E which in itself 65 forms the subject matter of the pending application, Serial No. 505,551 mentioned above, functions to apply variable braking action consecutively on the cores of the web rolls as these decrease in diameter while being fed to a printing machine and coacts with the present mechanism to tension or regulate the web of the roll in use and then to automatically transfer its tensioning or regulating action to the web of the replenishing web roll at the proper time. 70 75

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

10 What I claim is:

1. In web supply mechanism of the character described, in combination, a web roll support having a carrier member provided with means for rotatably supporting an exhausting web roll

15 and a spare web roll, a tension device secured to said mechanism for automatically applying tension consecutively to a web of each of said web rolls, said member being supported on means positioned between the exhausting and spare web rolls and within parallel planes tangent to the peripheries of said web rolls, whereby a substantial saving of space is effected in mechanism of the kind described.

20 2. In a web roll supply mechanism including in combination, a web roll support, means mounted on the support and adapted to rotatably support a plurality of web rolls, a tension device for applying a tension automatically and consecutively to a web of each of said plurality of web rolls in turn, and other means connected to the said support permitting the arrangement of the plurality of web rolls in adjacent positions to effect a substantial saving of space in mechanism of the kind described, said other means including a pair of shafts arranged between the web rolls and within parallel planes common to their peripheries.

25 3. A method of automatically transferring tension applied to an expiring web roll while rotating, to a replacement web roll which consists in revolvably mounting said expiring and replacement web rolls upon separate means secured to a support having a pair of interconnected power-transmitting instrumentalities, each of said power-transmitting instrumentalities being connected to separate tensioning means and to said expiring and replacement web rolls, then causing the revolution of the replacement web roll, as a web of said rotating expiring web roll is being fed to a printing machine after arranging said power-transmitting instrumentalities so that tension will be applied to the expiring web roll but not to the replacement web roll, then revolving said replacement web roll so that the power-transmitting instrumentalities connected to same rotates faster than the power-transmitting instrumentalities connected to said expiring web roll whereby the tension being applied to the expiring web roll is automatically transferred 30 therefrom to the replacement web roll.

40 4. In web supply mechanism for a printing machine, of the character described including a rotatable web roll support having a plurality of means for rotatably supporting a plurality of web rolls thereon, a tension device secured to said mechanism, and other means operatively connecting said plurality of means with said tension device when said web rolls are unwinding; each of said first-mentioned means including a plurality of clutches operative to join the tension device selectively to the plurality of means, one at a time only when the adjacent web roll begins to unwind.

45 5. A device for automatically transferring braking action from one revolving web roll to

another revolving web roll without interruption during the operation of a printing machine to which said device is operatively connected, comprising a web roll support having a plurality of means for rotatably supporting a corresponding plurality of web rolls, web tensioning means secured to said support, and other means including a plurality of over-running clutches automatically connectible to said tensioning means and to said first-mentioned plurality of means, for applying tension to said web rolls individually as each of the web rolls is fed to said printing machine to replace another of the web rolls approaching exhaustion.

50 6. In web roll supply mechanism for a printing machine including a web roll carrier including means adapted to rotatably support a plurality of web rolls, one of said web rolls having a web feeding to said printing machine, an individual over-running clutch for each of said plurality of means, a web tensioning instrumentality secured to said mechanism and connectible with the said clutches, and adapted to apply a variable tension to the said feeding web while simultaneously permitting by means of said clutches, rotation of another of said web rolls until the said feeding web has been operatively joined to a web of the last-mentioned roll.

55 7. In web supply mechanism for a printing machine of the character described including a web roll carrier, a plurality of means for rotatably supporting a plurality of web rolls on said carrier, a plurality of clutches connected to said means, said clutches being operative only when said web rolls are being fed to said printing machine, and a tension device automatically connectible to each of said plurality of means in turn for applying tension to same through said clutches and transferring said tension automatically from a feeding web roll approaching exhaustion to a fresh web roll.

60 8. A device for automatically transferring tension from a traveling web of an exhausting web roll to a web of a spare web roll without interruption to the operation of a printing machine to which said device is operatively connected which comprises in combination a tensioning instrumentality, a web roll support having a pair of means for rotatably supporting an exhausting web roll and a spare web roll, a clutch connected to each of said pair of means and to said tensioning instrumentality, said clutch being free running in one direction but adapted to resist by means of said tensioning instrumentality the rotation of said exhausting web roll while unwinding until the angular speed of the means supporting the spare web roll exceeds the angular speed of the means supporting the exhausting web roll and then operating to apply braking action to said spare web roll.

65 9. In web supply mechanism including a web roll carrier, a pair of means secured on said carrier and arranged in opposed relation thereon for rotatably supporting a pair of web rolls, a pair of shafts joining said means, said shafts being arranged between the web rolls and within parallel planes tangent to the peripheries of the said web rolls, a third shaft positioned between the pair of web rolls and the first-mentioned pair of shafts, said third shaft being operatively connected to each of said means, a tension device secured to the third shaft, and a common axial support for permitting the rotation of the pair of means, the pair of web rolls and all of said shafts as a unit.

10. In a support for two web rolls which are successively advanced to feeding position, a pair of shafts arranged in spaced relation, a pair of members adjustably mounted on said shafts for rotatably supporting the said web rolls, and means pivotally arranged on said support whereby the said shafts, web rolls and means may be rotated as a unit. 5
11. In a support for two web rolls which are successively advanced to feeding position, a pair of shafts arranged in spaced relation, a pair of members adjustably mounted on said shafts for rotatably supporting the said web rolls, a third shaft arranged between said first pair of shafts 10 and said web rolls, said third shaft being operatively connected to and rotated by the web rolls, a braking device fastened to the said third shaft and adapted to resist rotation thereof, and means including an over-running clutch associated with each of the web rolls whereby the roll which is 15 rotating at the higher speed will be connected to the braking device. 20
12. In a support for two web rolls which are successively advanced to feeding position, a braking device adapted to resist rotation of either 25 of the rolls, and means including an over-running clutch whereby the roll which is rotating at the higher speed will be connected to the braking device. 30
13. In a web supply mechanism including spaced pedestals, a web roll carrier rotatably supported by the pedestals, the web roll carrier including spaced parallel shafts, web roll supporting arms carried by the spaced shafts, and trunnion members rigidly secured to the parallel shafts and journaled on the pedestals. 35
14. In a web supply mechanism including spaced pedestals, a web roll carrier rotatably supported by the pedestals, the web roll carrier including spaced parallel shafts, web roll supporting arms slidably supported by the parallel shafts, and trunnion members rigidly secured to the parallel shafts and journaled on the pedestals to permit rotation of the web roll carrier. 40
15. In a web supply mechanism including spaced pedestals, a web roll carrier rotatably supported by the pedestals, the web roll carrier including spaced parallel shafts, roll supporting arms, a hub formed on each web roll supporting 45 arm and having spaced apertures formed therein for the reception of the said shafts thereby slidably mounting the web roll supporting arms on the said shafts, and trunnion members rigidly secured to the said shafts and journaled in the pedestals to permit the rotation of the web roll carrier. 50
16. In a web roll supply mechanism having axial supports for rotatably supporting web rolls, an overrunning clutch operably connected to each axial support, a braking device, means for 60 operably connecting the braking device to the overrunning clutches, the clutches being constructed and arranged so that while one of the clutches is imparting a braking action to its axial support and web roll the other is idling relative to its axial support and web roll. 65
17. In combination with a printing machine, means for rotatably supporting a plurality of web rolls, overrunning clutches operably connected to the web rolls, a braking device operably connected to the overrunning clutches, the clutches being constructed and arranged to automatically transfer braking action from one of the web rolls to the other as one web roll is substituted for another. 70
18. In combination with a printing machine, 75 means for rotatably supporting a plurality of web rolls, overrunning clutches operably connected to the web rolls, a braking device, means for operably connecting the braking device to the overrunning clutches, the said clutches being constructed and arranged to impart braking action to the running web roll and to idle relative to the reserve web roll, and to automatically transfer braking action from one of the web rolls to another as one web roll is substituted for another. 10
19. In combination with a printing machine, means for rotatably supporting a plurality of web rolls, an overrunning clutch operably connected to each web roll, a common braking device, means for operably connecting the said braking device to each overrunning clutch, the said clutches and connecting means being constructed and arranged to impart braking action to the running web roll and to automatically transfer braking action from one of the web rolls to another as one is substituted for another. 15
20. In combination with a printing machine, means for rotatably supporting a plurality of web rolls, an overrunning clutch operably connected with each web roll, a shaft, means for operably connecting each overrunning clutch with the shaft, a braking device operably connected with the shaft, the overrunning clutches and connecting means being constructed and arranged to impart braking action to the running web roll and to automatically transfer braking action from one of the web rolls to another as one is substituted for another. 20
21. A method of feeding webs to a running printing machine, which consists in revolvably 35 mounting a plurality of web rolls on a rotatable support, automatically applying uniform tension to the web of the running roll without operably engaging its web, rotating the support to move the reserve roll to a position to substitute for the 40 exhausting running roll, securing the web of the exhausting running roll to the reserve roll thereby making it the new running roll, and automatically transferring the tension from the exhausted roll to the new running roll. 45
22. Web controlling mechanism including in combination a movable support for a web roll rotatably mounted by its shaft, a brake operating on the roll shaft mounted on a stationary support, and means for connecting said web roll to said 50 brake to control the rotation of the roll. 50
23. Web controlling mechanism including in combination a movable support for a plurality of web rolls rotatably mounted by their shafts whereby web rolls may be successively brought into 55 active or feeding position, a brake operating on any of the roll shafts mounted in a fixed position and connections between said brake and web rolls whereby the brake controls the rotation of the active web roll. 60
24. Web controlling mechanism including in combination a rotatable support for rotatably supporting a plurality of web rolls, a brake for said web rolls mounted on the axis of rotation of said support and means for connecting said brake 65 to any of the web rolls. 65
25. Web controlling mechanism including in combination a rotatable support for rotatably supporting a plurality of web rolls, a brake for said web rolls mounted centrally of said web rolls, 70 and gearing connecting said brake with any one of said web rolls. 70
26. Web controlling mechanism including in combination a pair of rotatable arms between which are rotatably mounted a plurality of web 75

rolls to be successively moved into web feeding position, a brake mounted coaxially with said arms and chains driven by said rolls and connecting said brake with any of the web rolls.

5 27. Web controlling mechanism including in combination a pair of rotatable arms between which are rotatably mounted a plurality of web rolls to be successively moved into web feeding position, brake mechanism, a stationary support at a distance from said rotatable arms and on which said brake mechanism is mounted and means for operatively connecting said brake mechanism with any one of said web rolls.

10 28. Web controlling mechanism including in combination a pair of rotatable arms between which are rotatably mounted a plurality of web

rolls to be successively moved into web feeding position, brake mechanism, a stationary support at one side of the web rolls and on which the brake mechanism is mounted, a sprocket coaxial with said arms, a chain connecting said sprocket and brake and other chains individually driven by said web rolls and connecting said sprocket and web rolls.

15 29. A web tensioning means including in combination means for rotatably supporting a plurality of web rolls, a brake, gearing connecting the brake mechanism with each web roll, said gearing including one-way clutches whereby the brake is driven only by the fastest moving web roll.

JOHN R. TOMLIN.
